United States Patent Office

Des. 206,268
Patented Nov. 22, 1966

206,268

DATA PREPARATION CONSOLE

Walter J. Zenner, Des Plaines, Ill., assignor to Teletype Corporation, Skokie, Ill., a corporation of Delaware

Filed Sept. 30, 1964, Ser. No. 81,953

Term of patent 14 years

(Cl. D26—5)

FIG. 2

FIG. 1 is a front perspective view of a data preparation console, showing my new design; and

FIG. 2 is a rear perspective view thereof.

The essential features of my design are shown in full lines in the drawings.

I claim:

The ornamental design for a data preparation console, substantially as shown and described.
